ROTATABLE WAVE GUIDE JOINT

Andrew Alford, Cambridge, Mass., assignor to the
United States of America as represented by the
Secretary of War

Application April 9, 1946, Serial No. 660,602

1. Claim.

This invention relates to electrical apparatus, and more particularly, it relates to a radio frequency rotating joint. In transmission systems for conducting radio frequency energy from one point to another through wave guides, the need frequently arises for mechanically rotatable joints which permit portions of the transmission system to be moved rotationally with respect to other portions while at the same time the transmission of radio frequency energy is uninterrupted.

In the prior art, one typical means for meeting this need has been apparatus including round-wave-guide portions mechanically rotatable with respect to each other. Round wave guide lends itself to this use because of the axially symmetrical field configuration within it. However, there are certain drawbacks to this type of apparatus. For one thing it is rather critical as to frequency and may constitute the pass band width-limiting element in a system otherwise capable of broad band transmission. It follows that excessive reflection will occur for relatively small variations in operating frequency, that is, for variations beyond this narrow pass band, and that standing wave ratios of such systems will be adversely affected.

It is an object of this invention to provide a rotatable joint which is capable of operation over relatively broad frequency band. It is also an object of this invention that this rotatable joint have a low coefficient of reflection.

Other objects, features and advantages of this invention will suggest themselves to those skilled in the art and will become apparent from the following description of the invention taken in connection with the accompanying drawing in which:

Fig. 1 is a side view of one embodiment of this invention. This embodiment consists of two plane - to - circular - polarization transformers placed with corresponding ends face to face.

Fig. 2 is a cross-sectional drawing of a broken away portion of the device shown in Fig. 1 showing, as an added element, an RF choke.

Generally, this invention consists of a combination of two radio frequency horns each of which is capable of transforming plane-polarized energy into circularly polarized energy and vice versa. This transformer is described in my pending application, Serial No. 644,175, filed January 25, 1946. These horns consist of a rectangular wave guide section joined axially with a tapered horn outlet at one end and, at the other

(Cl. 178-44) 2. The combination of a waveguide having a rectangular cross section, a transition portion, and a rectangular wave guide, the transition portion being located at one end, through a transition portion to a conventional rectangular wave guide. Radio frequency energy, such as energy in the microwave range of frequencies, (i. e., having wave lengths of the order of centimeters) is supplied to the device by means of the conventional rectangular wave guide. It will be understood that the term rectangular, applied to the cross section of these wave guide portions, is intended to include an effective rectangular wave guide section such as an elliptically shaped section which may be produced by rounding the corner of a rectangular shaped section. The cross sectional dimensions of the wave guide section are preferably larger than the corresponding dimensions of the wave guide. Also, the wave guide section is angularly displaced about the longitudinal axis of the radio frequency horn with reference to the wave guide so that the planes of the wave guide section are at substantially an angle of 45° to the planes of the wave guide. A tapered portion is used to effect the transition between the wave guide section and the wave guide. This preferably comprises eight triangularly shaped pieces. 10 The direction of the electrical vectors of the energy waves arriving at one end of the transition portion is parallel to one of the sides of the wave guide. While traveling along the transition portion the electrical vector is directed along the diagonal of the cross section of the wave guide section. By the time the wave arrives at the junction of the transition portion and the wave guide section, the electrical vector is effectively resolved into two mutually perpendicular components parallel to the sides of the wave guide section. By making the cross sectional dimensions both greater than a half wavelength of the energy being transmitted it is possible for the two component waves to be propagated along the length of the wave guide section. 20 Both component waves are of transverse electrical type and each behaves in much the same manner as a transverse electrical wave in a conventional wave guide. The phase velocities at which the two-component waves are propagating are different from one another when the wave guide dimensions are unequal. Because of this difference in velocities, there is a progressively increasing phase difference between the two electric vectors which are at right angles to each other in space. After the two component waves have propagated over a suitable distance, the time phase distance between the two electric vectors becomes equal to 90° so that these vectors

are not only in space quadrature but also in time quadrature thereby resulting in circularly polarized energy waves.

This is the case at the beginning of the tapered horn. The aperture of the tapered horn may be made approximately square and the flare is usually fairly short, so that the difference in phase does not continue to increase within the horn. The result is that the tapered horn acts merely as a transformer or as an impedance matching section between the wave guide section and space—or a similar horn—reducing the reflection at the end of the wave guide section to a small value. When the flare is made gradual, further small phase differentiation may occur within the tapered horn. This, however, may be allowed for by making the length of the wave guide section somewhat shorter.

Referring now more particularly to Fig. 1, transforming horn 1 consists of four principal components. These components are rectangular wave guide 2, section 3 of wave guide, transition portion 4 for mechanically and electrically joining wave guide 2 and section 3 and tapered horn 5 which increases the characteristic impedance of section 3. The detailed structure of horn 1 and the physical arrangements of its principal parts are fully described above and further in my copending application referred to above.

In operation, plane polarization rectangular wave guide 2 feeds into, or is fed by, section 3. If radio frequency energy is fed through rectangular guide 2 in the direction of tapered horn 5, it becomes circularly polarized and the electric vector of the radio frequency energy which emerges from tapered horn 5 is a rotating one of relatively constant magnitude.

Transforming horn 6 corresponds to horn 1 in structure and function. It can be proven theoretically, and it has been established experimentally, that if circularly polarized radio frequency energy is fed into the end of the tapered horn portion of transforming horn 6 which is coupled to tapered horn 5 of transforming horn 4, that it will be translated into plane polarized radio frequency energy at the end of transforming horn 6 which is coupled to rectangular wave guide 2. Horn 6 will affect this transformation irrespective of the angular position of the electric vector of the input energy at any instant of time.

It can be proven theoretically and it has been established experimentally that a corresponding transformation will be effected if energy is transferred in the opposite direction, that is from horn 6 into horn 1.

As a result of the manner of operation of this device, rectangular wave guide 2 of transforming horns 1 and 6 may have any axial rotational relationship with respect to each other and nevertheless the radio frequency energy passing through them will be plane polarized; moreover the flow of power will be uninterrupted not only irrespective of their respective axial rotational relationship but also irrespective of any rate at which they might be moved rotationally with respect to each other, within all practical mechanical limits.

Referring now more particularly to Fig. 2 it will be seen that a radio frequency quarter wavelength choke can readily be added to this apparatus at the point of juxtaposition between the two plane-to-circular-polarization transforming devices.

The RF choke shown in Fig. 2 is perfectly

conventional in every way and it is unnecessary to describe it in detail.

Section 3 of horn 1 and the section of horn 6 which corresponds to it are not as frequency sensitive as are round wave guides. For this reason, the pass band of this rotating joint is governed primarily by the characteristics of other portions of the system. If transition portion 4 is made to have a length of the order of one wavelength corresponding to the lowest intended operating frequency, it will not create a sudden discontinuity which might set up substantial reflections. In the same way, tapered horn 5 of transforming horns 1 and 6, change the characteristic impedance of the guide to which they are attached in a gradual enough manner to avoid undesirable electrical discontinuities.

Therefore, this apparatus is capable of operation over a relatively broad frequency band and for its frequency band of operation it has a low coefficient of reflection.

It is obvious that plane-to-circular-polarization transforming devices can be employed which are not of the type used in this embodiment and described in the copending application mentioned above. In fact, any one of a variety of plane-to-circular-polarization transforming device may be employed in other embodiments of this invention which follow the same basic principle of operation. The basic principle of this invention is that of transforming plane polarized energy into circularly polarized energy and then transforming it back again into a plane polarized condition. In this respect it is distinguishable from ordinary rotating joints which transform plane polarized energy into energy which, within a round wave guide, has an axially symmetrical field configuration but is not circularly polarized.

It is obvious that the mechanical details of construction of this apparatus may be selected from a wide variety of conventional techniques. It is also obvious that mechanical structure for supporting said horns and mechanical drive means for rotating them axially with respect to each other may be fashioned in accordance with any of a wide variety of well known conventional designs. This wide variety of choices in the matter of construction of this apparatus can be exercised without departing from the spirit and scope of this invention.

It will be apparent that there may be deviations from the invention as described and claimed which still fall fairly within the spirit and scope of the invention.

What is claimed is:

A device for coupling linearly-polarized electromagnetic waves from a fixed to a rotatable rectangular wave guide over a broad operating frequency band comprising first and second rectangular wave guides for translating linearly-polarized electromagnetic waves, one of said wave guides being fixed and the other being rotatable, first and second rectangular wave guide sections having their surfaces displaced 45° from the surfaces of said first and second wave guides, respectively, first and second wave guide transformer sections coupled between said first and second wave guides and said first and second wave guide sections, respectively, and shaped to transform linearly-polarized electromagnetic waves into a pair of waves linearly-polarized perpendicularly to one another, said wave guide sections having cross-sectional dimensions large enough to propagate said pair of waves polarized

perpendicular to one another and having a length to provide a 90° phase shift between said pair of waves, and first and second tapered horns coupled respectively to said first and second wave guide sections and tapered to a substantially square open end which is substantially impedance-matched to space over a broad operating frequency band, said horns being mounted with said open ends adjacent one another.

ANDREW ALFORD.
